TELEPHONE KEY

Leslie B. Haigh, West Orange, and Franklin A. Stearn, Westfield, N. J., assignors to Federal Telephone and Radio Corporation, New York, N. Y., a corporation of Delaware

Application May 6, 1944, Serial No. 534,420

2 Claims. (Cl. 179—176)

1

This invention relates to electrical switching keys of the type known as lever keys and more particularly to such keys designed for use in places where space is at a premium.

One object of this invention is to provide a lever key which will be easy to manufacture and which will require the minimum number of parts in manufacturing.

Another object of this invention is to provide a key in which the frame and actuating cam assembly is held together by means of a single screw, this screw likewise mounting the spring assembly or assemblies upon the frame proper of the key.

Yet another object of this invention is to provide a key in which only a single type of cam is employed whether the key be a two or a three position key and whether locking or non-locking action be required, and in which pairs of oppositely disposed holes are provided in the key frame, in which holes a stop pin or pins may alternatively be placed to determine the extent of rotation of the cam and the extent of throw of the key.

Another purpose of this invention is to provide a key in which economical assembly is promoted by arranging the cam rollers so that they run freely upon the cam stud and are held thereupon by a portion of the frame.

Other purposes and advantages of this invention will be apparent to those skilled in the art from a consideration of the drawings hereunto appended, where

Fig. 1 represents a single sided key, in front elevation and unoperated position.

Fig. 2 represents a single sided key, in front elevation and in operated position.

Fig. 3 shows the same key in side elevation and unoperated position.

Fig. 4 shows, in rear elevation, the same key in unoperated position.

Fig. 5 is a top plan view of the same key.

Fig. 6 is a front elevation, of a double sided key according to this invention, shown in unoperated position.

Fig. 7 is a front elevation of a double sided key in operated position.

Fig. 8 is a side elevation of a double sided key, in unoperated position; and

Fig. 9 is a side view of the cam employed in this key.

2

The single sided key of this invention shown in Figs. 1 to 5 includes two side plates 10 and 11, held together by a single screw 12. A locating stud 13 pressed out of or secured in each plate 10 registers in a corresponding aperture in the other plate, although the actual clamping together of the plates is accomplished solely by means of screw 12. Screw 12 passes through holes in the plates 10 and 11 and through a spring assembly member 14, and is secured by a square nut 12' which sits in a recess in member 14. Member 14 has, fastened upon the sides thereof by means of screws 15, two spring assemblies 16 and 17, located upon the opposite sides of member 14. The number of contact springs forming each of these two assemblies and their interconnection and operation with respect to opening and closing various contacts, is not material to this invention, since the number of springs used and these various interrelationships can be determined according to the particular use to which the key is to be put.

More rigid members 18 and 19 may be provided in order to limit the motion of certain springs, if so desired. The actuation of the springs upon the respective sides of member 14 is brought about by actuating contact springs 20 and 21, which are elongated above the ends of the other contact springs and have the elongated portions thereof formed in such fashion that roller 22 will cause lateral motions of the actuating springs. Roller 22 rotates freely upon cam stud 23, and stud 23 is mounted upon a portion of the cam body 24, which latter is provided with a suitable handle 25. The roller 22 is prevented from running off the end of the stud by means of a lip 26 which projects downwardly from the upper portion of frame member 10. This avoids the necessity of riveting a washer upon the stud after the roller has been placed thereupon, or otherwise retaining the roller in position thereupon.

Frame members 10 and 11 are provided with oppositely located bearing apertures 30'. Cam body 24 is provided with a bearing 50, of the hollow shaft type, which rotates upon a pin 30. This pin has the two ends thereof inserted into the pair of corresponding apertures 30', at the time when the key is assembled. Frame members 10 and 11 are also provided with suitable apertures 29 and 29', registering with one another 50 when the respective frame members are as-

sembled. These apertures may be utilized for limiting the key motion to the desired extent by placing pins in the apertures. According to the pair of apertures 29 which is chosen to act to hold the stop pins for the cam 24, the functioning of the cam may be arranged so that the key can assume any one of five possible operative combinations; namely,

- Single non-lock
- Single lock
- Double non-lock
- Double lock
- Lock on one side, non-lock on the other side.

If the key is to be "locking" on either side, no pin 54 is used on that side the motion of the cam being limited only by the projection 52. In this extreme position the tension of the spring 20 or 21 is exerted against the roller 22 in such direction that it holds the cam in its operating position by a toggle action. A pin in the pair of upper holes on either side makes it "non-locking" on that side since the force applied by the spring against the roller is in such a direction that it will return the cam to its medial position when the key is released. A pin in the pair of lower holes on either side blocks the cam against rotation on that side and converts the key into a two-position or "single" key.

One form of stop pin is indicated at 54 in the drawings, and is preferably identical with pin 30.

Referring now to the double sided form of key shown in Figs. 6, 7 and 8, the frame is here constituted by two substantially identical members 40 and 41. Spring assemblies are arranged upon both sides of these frame members, the members being held together by screw 12', which passes also through the mounting members 14' of both spring assemblies. In this case, also, this allows the employment of a single screw to hold the frame members together and the spring assemblies thereto, thus saving time in assembly and reducing the cost of manufacture.

The number of springs and the arrangements of contacts employed in this form of key are not essential features of the instant invention and may be selected according to the desired functioning of the key. The members serving to actuate the contact springs are similar to those previously shown and described in connection with the single sided form of key and here bear corresponding reference numerals.

In the double sided key, each frame member 40 and 41 is provided with its own fastening apertures located upon the extreme upper surface thereof, into which apertures fastening screws 42 and 43 may be threaded.

The alignment of the two frame members is maintained by studs 13' one pressed out of or secured in each frame member. Oppositely disposed pairs of apertures 29' are provided in the upper portion of frame members 40 and 41, so that the pins 54 used as stops for the cam may have their positions suitably determined at the time of assembly, according to the particular function which the key is to perform. Accordingly the double sided key may likewise be utilized in any one of the five possible operative combinations, as above detailed in describing the single sided key.

In the double sided key, there are provided two cam studs 23', located upon opposite sides of the cam body 24' and each stud bears a cam roller

22'. In this case, likewise, a suitable lip 26' extends downwardly from the upper portion of each frame member 40 and 41, so that the cam rollers are prevented from running off the ends of the respective studs upon which they rotate.

In both the single and double sided forms of key according to this invention, the extreme angular rotation of the cam may be limited by suitable means, which do not form an essential part of the instant invention. For example, the lower portion of the cam may be provided with one or more projections, 51 in the single key and 51' in the double key, which encounter a limiting or stop projection 52 or 52', provided upon one or both of the frame members in the two forms of key.

Fig. 9 shows the cam provided with main stop projections 51 and ancillary stop projections 55, these latter being located at a shorter distance from the axis of rotation of the cam than are projections 51. This arrangement permits the uppermost apertures to be located at a sufficient distance from the top of the key to enable insertion of the mounting screws 42, 43 without fouling the stop pin when it is inserted in these apertures. According to the particular pair of apertures 29 or 29' chosen, stop pin 54 will encounter one only of the stop projections 51 or 55, thus allowing the degree of angular rotation of the cam to be determined by such selected position for the stop pin, since the respective radii of the various pairs of apertures with respect to the axis of rotation of the cam are not identical but are varied so that the desired cam projection may be engaged with the stop pin.

Modifications and alterations of the keys above described by way of example, will be apparent to those skilled in the art and this invention is limited only by the scope of the hereunto appended claims.

What is claimed is:

1. A switching key comprising a frame, a rotatable cam mounted upon a pivot in said frame, contact springs operable by said cam, a projection on the periphery of said cam, a plurality of pairs of oppositely disposed holes in said frame, said pairs of holes being located at different angular positions relative to the said pivot and at such radial distance from said pivot that said cam projection passes over each of said pairs of holes during rotation of said cam and a removable pin for insertion in any one of said pairs of holes for cooperation with said projection whereby the degree of rotation of said cam and the extent of throw of the key may be varied.

2. A switching key comprising a frame, a rotatable cam mounted upon a pivot in said frame, contact springs operable by said cam, a plurality of projections on the periphery of said cam having cam surfaces at different radial distances from said pivot, a plurality of pairs of oppositely disposed holes in said frame, said pairs of holes being located at different radial distances from said pivot such that said projections each pass over one of said pairs of holes during rotation of said cam and a removable pin for insertion in any one of said pairs of holes for cooperation with said projections whereby the degree of rotation of said cam and the extent of throw of the key may be varied.

LESLIE B. HAIGH.
